UNITED STATES PATENT OFFICE.

VIRGINIA WHITEHEAD GLOVER, OF SAVANNAH, GEORGIA.

FOLDING TABLE FOR SEWING-MACHINES.

SPECIFICATION forming part of Letters Patent No. 781,415, dated January 31, 1905.

Application filed September 9, 1904. Serial No. 223,894.

To all whom it may concern.

Be it known that I, VIRGINIA WHITEHEAD GLOVER, a citizen of the United States, residing at Savannah, in the county of Chatham and 5 State of Georgia, have invented certain new and useful Improvements in Folding Tables for Sewing-Machines; and I do declare the following to be a full, clear, and exact description of the invention, such as will enable 10 others skilled in the art to which it appertains to make and use the same, reference being had to the accompanying drawings, and to the letters of reference marked thereon, which form a part of this specification.

15 This invention relates to new and useful improvements in folding tables for sewing-machines; and the object of the invention is to produce a simple and efficient device of this character which may be readily attached to 20 an ordinary sewing-machine and which when not in use may be folded out of the way.

The invention consists, further, in various details of construction and combinations of parts, which will be hereinafter fully described 25 and then specifically defined in the appended claim.

My invention is illustrated in the accompanying drawings, which, with the letters of reference marked thereon, form a part of this 30 application, and in which—

Figure 1 is a perspective view of the upper portion of a sewing-machine, showing my improved folding table opened in readiness for use. Fig. 2 is a perspective view showing the end wings of the table folded in. Fig. 3 is a side elevation of the machine with the drawer folded in, and Fig. 4 is a sectional view on line 4 4 of Fig. 3.

Reference now being had to the details of 40 the drawings by letter, A designates the top of a sewing-machine of ordinary construction, and B designates series of drawers on either side of the machine below the top.

Mounted in suitable guideways (designated 45 in the drawings by letters C) is my improved table, comprising two central sections D and D', which are hinged together at d, said sections being of equal width and one adapted to fold upon the other when not in use. In order 50 to make a longer table, I provide end wings

E and E', which are hinged to the sections D and D', respectively, at e. The inner marginal edge of each wing E has a notch F, (shown clearly in Figs. 1 and 2 of the drawings,) and the outer marginal edge of each wing 55 E' is notched, as at F', which notches are provided for the purpose of allowing the table when folded to push back upon the guideways without interference with the legs H of the machine. 60

Intermediate the two sets of drawers B is a central drawer I, and J J designate bracket-arms, which have a longitudinal movement through strips J' at the sides of said drawers B. Said drawer I and the bracket-arms are 65 adapted to be drawn out for the purpose of forming supports for the folding table-sections in the manner shown in Fig. 1 of the drawings, and when it is desired to utilize the end wings the top drawer of each series B is 70 drawn out in the manner shown in Fig. 1 of the drawings to form a rest for the wings.

O designates hooks which are pivotally mounted upon the sections E' and are adapted to engage headed pins or screws O', fastened 75 to the sections or wings E, whereby the two wings on each end may be held in the same plane.

When it is desired to utilize a shorter table, the two end wings E and E' may be folded 80 upon the upper surfaces of the sections D and D', respectively, as shown in Fig. 2 of the drawings, in which adjustment the brackets J may be utilized for supporting the hinged ends of the sections D and E. 85

By the provision of the construction shown and described as embodying my invention it will be observed that a simple and efficient folding table is provided which may be applied to any ordinary sewing-machine by first withdrawing the upper drawers and utilizing the drawer-cleats for supports for the table, or when constructing a machine with the view of having the table a permanent fixture therefor special provision may be had for the reception of a table in the manner shown in the drawings. 95

While I have described a particular detailed construction of folding table embodying the features of my invention, it will be under- 100

stood that I may vary the same, if desired, as to details without in any way departing from the spirit of the invention.

Having thus fully described my invention, 5 what I claim as new, and desire to secure by Letters Patent, is—

In combination with the frame of a sewing-machine table having a top and legs supporting the same, an elongated recess underneath 10 the top, a leaf made up of a central section and end sections hinged thereto, each of said sections being further composed of an inner and an outer section, adapted to fold one upon another to slide within said recess and to be extended therefrom, sliding bars flush with the 15 bottom of said recess adapted to be extended

to form supports for the table, drawers mounted to slide in said frame with their tops flush with the bottom of said recess, and adapted to form supplemental supports for the end sections of the leaf, the inner and outer sections of the said end sections having notches, designed to register and to receive the legs, when said sections are folded together within the recess, as set forth. 20

In testimony whereof I hereunto affix my signature in presence of two witnesses. 25

VIRGINIA WHITEHEAD GLOVER.
